TRACTION SPLINT

Raymond Hartmann and Gustave R. Tifal,
Los Angeles, Calif.

Application October 26, 1942, Serial No. 463,394

6 Claims. (Cl. 128—84)

Our invention relates to surgical devices, and has among its objects and advantages the provision of an improved quick application traction splint equally well suited to arm or leg work.

In the accompanying drawing:

Figure 1 is a view illustrating our invention applied to leg and arm conditions.

Figure 2 is a perspective view of the splint.

Figure 3 is a longitudinal sectional view.

Figure 4 is a detail view of a telescopic clamp, 10 and

Figure 5 is a sectional detail view illustrating a traction spring.

In the embodiment of the invention selected for illustration, we make use of a tubular member 10 within which is slidably fitted a shaft 12. This shaft is provided with a curved groin or armpit engaging crosspiece 14. The outer end of the member 10 is provided with a laterally positioned arm 16 recessed to provide fingers 18 between which is positioned a shank 20 of a pressure clamp 22 having a cupped or concaved face 24.

A compression spring 26 has one end housed in a bore 28 in the outer end of the member 10. The other end of the spring lies in a recess 30 in one face of the traction clamp 22, this end of the spring being held in place by a plate 32 fastened to the traction clamp and inserted between two convolutions of the spring. The spring 26 normally holds the traction clamp in the position of Figure 3, but the traction clamp may be pivoted toward the member 10 about the axis of a pin 34 which pivotally connects the traction clamp with the fingers 18.

The inner end of the member 10 is slotted at 36 and recessed circumferentially at 38 for the reception of a clamp band 40. A leather strap 42 is interposed between the band 40 and the recessed part of the member 10 to protect the latter, since the two sections 10 and 12 may be formed of wood. A bolt 44 is provided for tightening the clamp band 40 on the member 10. Thus the members 10 and 12 are telescopically related and may be fixedly related in different positions to vary the length of the splint.

A top strap 46 is attached to the member 12 and is provided with a buckle 48. An intermediate strap 50 is attached to the member 10 and also includes a buckle 52. The third strap is attached to the traction clamp 24 and is provided with a strap 54 and a buckle 56.

In operation, the splint may be applied to either the arm or the leg. The part 14 is placed against the groin or in the armpit. The clamp

40 is loosened and the two members 10 and 12 adjusted to the desired length according to the size of the patient's arm or leg. The strap 46 is then securely fastened around the arm or the leg. For leg purposes, the strap 54 is then passed about the ankle for securely attaching the latter to the pressure clamp 22. The members 10 and 12 are then extended sufficiently far to compress the spring 26 and bring the pressure clamp 22 to the right angular position of Figure 1. The clamp 40 is then tightened and the strap 50 moved upwardly or downwardly of the member 10 to its proper position and tightened around the arm or the leg. The patient is then ready for transportation.

For arm purposes, a standard cravat bandage hand hitch 58 connects the arm with the pressure clamp 22 to hold the latter in its right angular position. When once applied, the spring 26 provides a constant traction of the required pressure, which is usually around forty-five pounds or slightly less. The maximum area of the injured limb is exposed while the traction splint is applied thereto so that wounds may be cared for without removing the splint. The straps hold the splint firmly against the injured member and at the same time helps to maintain the traction.

Without further elaboration, the foregoing will so fully explain our invention, that others may, by applying current knowledge, readily adapt the same for use under various conditions of service.

We claim:

1. A traction splint comprising telescopically related first and second sections, means for fixedly relating the sections, a body engaging member at one end of said first section, a pressure clamp pivotally connected with the outer end of said second section, and resilient means acting on said pressure clamp and said second section.

2. A traction splint comprising telescopically related first and second sections, means for fixedly relating the sections, a body engaging member at one end of said first section, a pressure clamp movably connected with the outer end of said second section, and a spring acting on said second section and said pressure clamp to yieldingly bias the latter to a traction position.

3. A traction splint comprising telescopically related first and second sections, means for fixedly relating the sections, a body engaging member at one end of said first section, a pressure clamp pivotally connected with the outer end of said second section and having a recess, said

second section having an axial bore in its outer end, and a compression spring interposed between the second section and said pressure clamp and having its ends respectively lying in said bore and said recess.

4. A traction splint comprising adjustably related first and second sections, means for fixedly relating the sections, a body engaging member at one end of said first section, a pressure clamp pivotally connected with one end of said second section, said second section having a projection lying to one side of said one end, and resilient means interposed between said pressure clamp and said second section.

10

5. The invention described in claim 4 wherein said pressure clamp is provided with an attaching strap, a second attaching strap slidably mounted on said second section, and a third strap carried by said first section.

6. The invention described in claim 1 wherein said means comprises a slotted end of said second section, and a screw tightened band encircling said slotted end.
